UNITED STATES PATENT OFFICE.

BENJAMIN GEORGE CLAUDE STEPHENS, OF AUCKLAND, NEW ZEALAND.

AUTOMATIC SWITCH FOR ELECTRIC HEATING APPLIANCES.

1,422,898.

Specification of Letters Patent. Patented July 18, 1922.

Application filed February 14, 1920. Serial No. 358,792.

To all whom it may concern:

Be it known that I, BENJAMIN GEORGE CLAUDE STEPHENS, subject of the King of Great Britain, residing at 208 Victoria 5 Arcade, Auckland, in the Dominion of New Zealand, electrical engineer, have invented a new and useful Automatic Switch for Electric Heating Appliances; and I do hereby declare the following to be a full, clear, and 10 exact description of the same.

This invention has been devised in order to provide an improved construction of automatic switch for electric heating appliances. It has been designed particularly for use 15 with electric irons but it is readily adaptable to other appliances in which electricity is the heating agency. Its purpose is to provide for the electric heating circuit being broken in a positive and effective manner 20 upon the temperature of the appliance reaching a predetermined point, and thereby to prevent any danger of fire from overheating in the event of the appliance being left with the current on for any length of time.

25 The adaptation of the invention to electric irons provides a simple and efficient means whereby all dangers from fires occurring through the iron overheating, are removed.

The invention consists in the combination 30 with a bi-metallic strip of well known expansive properties positioned in the appliance so as to be acted on by the heat thereof, of a switch apparatus of special design that when in position, is held against the action 35 of certain springs to close the heating circuit. This apparatus is also so constructed that it will be engaged by the strip when it moves to a certain extent, under the action of the heat, and freed so that its springs 40 will force it away and break the circuit.

The invention is herein described in relation to an electric iron and its application thereto is illustrated in the accompanying drawings, in which:—

45 Figure 1 is a side elevation of an iron, the ordinary plate cover being shewn in section in order to illustrate the position of the apparatus.

50 Figure 2 is a plan thereof, the cover being broken away to show the position of the strip.

Figure 3 is a cross sectional elevation of the iron showing the switch in its closed position.

55 Fig. 3^a is a detail sectional view of the same on a larger scale.

Figure 4 is a longitudinal section of the switch, such section being at right angles to that shewn in Figure 3.

Figure 5 is an underneath plan of the 60 switch.

Figure 6 is a plan of a portion of the iron cover showing it formed to receive the invention.

A is the usual sole plate of the iron, B the 65 resistance plate and C the cover secured over them. In this invention a bi-metallic strip D is arranged between the resistance plate and the cover; such strip being made in any of the approved ways governing the construction of such forms of thermostatic 70 appliances. It is shaped with a horse shoe bend so as to form a short leg that is secured to the inside of the cover C by the screws d and thus held from movement, and a long leg 75 that extends longitudinally beneath the cover and is left free. The expansion and contraction movement of the strip will therefore cause a lateral movement of this free end.

80 The switch apparatus consists in two contact blocks E E' that are arranged in the cover and fastened to an insulated plate F that is fixed beneath the cover, so that the blocks project upwards through apertures 85 G G' formed in the cover for that purpose.

A strip H of mica, or the like, overlies the cover top and surrounds the blocks so as to insulate them from one another and the cover. These blocks are arranged in the re- 90

sistance circuit of the iron so that when they are unbridged the circuit is broken. Combined with such contact blocks, is a cap piece J that is adapted to fit over the blocks and to be fastened to the cover by means of a lug 95 K on one side that hooks into an aperture K' on the cover, so as to engage beneath its edge, and a spring controlled hasp M that passes into another aperture M' on the cover and engages beneath it. The bottom of this 100

hasp is positioned adjacent to the free end of the strip D and its movement to free the cover is in the line of the movement of such free end when the strip expands. A regulating screw D' is screwed through the end 105 of the strip and this screw is adapted to engage the hasp and push it away from engagement with the cover, when the strip expands to the predetermined extent fixed by the adjustment of the screw D'. This action 110 will free the cap so that it may be lifted from the cover.

Inside the cap is a spring metallic bridge N that is fastened to one end of a folded leaf spring O, the other end of which is fastened to the inside of the cap and suitably insulated therefrom. This spring and bridge are adapted to be placed in strong compression when the cap is placed in position to cause the bridge to bridge the contact E and E', and to be locked to the cover, as shewn in Figure 3. This is the position the switch will retain under all normal circumstances, the heating circuit being completed through the bridging of the contacts. When, however, the heat reaches such a degree as to cause the strip to expand the necessary amount, its free end will engage and push back the hasp M, thereby permitting the compressed spring O to expand and throw the cap and bridge clear of the cover and thereby break the circuit in the required manner.

The circuit will then have to be manually restored by replacing the cap, the invention thus differing in its working from other automatic switches employing the thermostatic strip and in which the circuit is automatically restored on the lowering of the temperature to the normal.

I claim:—

1. In automatic switches for electric heating appliances, the combination with a bi-metallic thermostatic strip arranged within

the heating influence of an electric heating circuit embodying a pair of terminals, a switch constructed to bridge such terminals and held in position against the action of a spring normally forcing it on the terminals, and releasing means for the said switch adapted to be engaged and operated by the movement of the bi-metallic strip through its expansion beyond a predetermined extent, substantially as specified.

2. In automatic switches for electric heating appliances, the combination with a pair of heating circuit contact terminals, of a cap adapted to be fitted over such terminals and to be held in position by a spring hasp, a spring within such cap having a bridge piece attached thereto and adapted when the cap is in position to be compressed and to hold the bridge piece across the terminals, and a bi-metallic strip arranged within the heat influence having one end made fast, and the other free and positioned adjacent to the said hasp so as to engage and free it when the strip expands, substantially as specified.

In testimony whereof, I have signed this specification in the presence of two subscribing witnesses.

BENJAMIN GEORGE CLAUDE STEPHENS.
